CARDING MACHINE

Mitchell S. Fain, New Haven, Conn.

Application January 25, 1946, Serial No. 643,295

5 Claims. (Cl. 19—100)

1

This invention relates to carding machines which prepare fibres for spinning into yarns and thread. An important object of the invention is to provide a machine having improved operating characteristics, which is simpler in construction than conventional machines, which costs less to produce, which occupies only a fraction of the space of conventional cards, and which, by virtue of its fewer parts and other features of construction, requires less servicing than conventional carding machines.

The construction of carding machines has changed very little in the past fifty years. The common multiple unit machine is provided with a plurality of large rolls with the usual worker and stripper rolls. The breaker carding occurs in the first unit, after which the carded web is removed by the doffer, is condensed to a sliver, and is then lapped back and forth by the intermediate feed which is associated with the second unit. Passing through the second unit the stock is similarly carded, the carding being at a right angle to the first card. In the machines of the prior art, each set of cards has usually comprised three main rolls, and in many cases four main rolls are employed. The foregoing procedure is followed in spinning on the woolen system wherein the fibres are first carded in one direction and are then carded in a second direction. In the worsted system, however, the fibres are carded in only one direction. In the worsted system there is no intermediate feed, so all the fibres are carded in the same direction.

Machines of this type are expensive to construct and maintain, require a vast amount of floor space, and card a relatively small quantity of stock in a given unit of time.

So far as is known, all machines of the prior art utilize only the upper peripheral surface of the main carding roll, and accordingly it has been found necessary to employ a plurality of such main rolls in order to completely card the stock. One particular improvement of the present invention resides in the provision of a single main roll for both the breaker carding and the finished carding. This roll is of larger diameter than conventional rolls, and a plurality of worker and stripper rolls are disposed both along the lower periphery of such main roll and also along the upper periphery thereof. The breaker carding occurs along the lower periphery, and the final carding along the upper periphery. This arrangement may, of course, be reversed.

By forming the main roll of increased diameter, three important advantages are achieved.

2

The travel of the card clothing on the outer periphery of the main roll more nearly approximates a straight line than is the case with conventional carding machines. This makes for better carding action and avoids tearing of the fibres. The second advantage resides in the fact that there is sufficient room for an approved number of worker and stripper rolls, both below the lower half and above the upper half of the main roll, to complete the entire carding operation on the single roll instead of the three or four main rolls used in conventional machines. The third advantage of the larger roll resides in the fact that the centrifugal force at the periphery of the main roll is very considerably reduced, which results in a marked reduction in the amount of flyings, and a corresponding saving in stock since flyings are waste and are sold as such.

Suitable feeding means including a licker-in 20 are provided for delivering the uncarded stock on the main roll, and adjacent the last worker roll on the lower periphery there are provided fancy and doffer rolls, and an intermediate feed which laps the sliver back and forth. The partially carded stock is then fed back to the main 25 roll on its upper surface for the final carding operation. In the event that the carding is done by the worsted system, the intermediate feed may be removed and the carding action continued 30 entirely around the outer periphery of the single main roll.

The machine of the present invention is much easier to clean than is the case with conventional machines, and all of the parts, particularly the 35 worker and stripper rolls, are made readily accessible. The machine may be used for carding all fibrous materials, such as wool, cotton, flax, jute, asbestos, as well as synthetic staple fibres. The machine also supplies a uniform web of fibrous 40 material to be used for felting purposes or in connection with the manufacture of plastic bonded cloth.

Another object of the present invention is to provide an improved feed for carding machines. 45 This improved feed is much simpler than conventional feeds, is less expensive to construct, has fewer parts, provides a uniform web along the full working width of the machine, and also provides improved means for mixing different grades 50 and different types of fibres to obtain a more homogeneous web.

A further object of the invention is to provide improved means for mounting the worker and stripper rolls in carding machines as well as the 55 other rolls auxiliary to the main roll.

In the drawings:

Fig. 1 is a side elevation of a carding machine embodying the present invention.

Fig. 2 is an enlarged broken section taken on line 2-2 of Fig. 1.

Fig. 3 is a schematic view showing the arrangement of the main roll and the worker and stripper rolls, together with the feeding mechanism, the fancy rolls and the doffer rolls.

Fig. 4 is a broken elevation of the feeding means.

Fig. 5 is a section taken on line 5-5 of Fig. 4.

Fig. 6 is a top plan view of the sliver trough.

The first feed unit may comprise a hopper 10 which may, if desired, be open at the top and be supplied with the uncarded stock in any suitable manner. The trough may be of a length equal substantially to the width of the main roll, and the side walls of such trough converge inwardly, as shown. Adjacent the lower end of the hopper there is provided a rotating feed vane 11, and immediately below the feed vane the side walls of the hopper project outwardly, as shown at 12. Within this lower, enlarged portion there are disposed a plurality of spaced feed rolls 13 having the usual metallic clothing on their outer peripheries. The spacing of the feed rolls is such as to cause a slight intermeshing of the clothing. This arrangement is desirable, since if the feed rolls were spaced further apart the suction afforded by a suction pump positioned therebeneath would be such as to rob stock from the feed rolls. Below these feed rolls there is a receptacle 17. Suction pump 14 is connected with the receptacle at the lower end of the hopper, as shown at 15, and connected with this pump is a flexible tube 16 which terminates in a nozzle 20, which latter is suitably arranged in a feed trough 21. The feed trough may be of a length equal substantially to the width of the main roll.

The nozzle is mounted for reciprocating movement transversely of the trough 21 by the arrangement shown in Figs. 4 and 5, which may comprise a transverse track 22 having adjacent its upper end a dovetail element 23. A travelling block 24 may be provided at its upper end with a ring 25 which supports the nozzle. Block 24 is formed with an opening 26 which is shaped complementary to dovetail portion 23, and roller bearing means 30 may be provided to reduce friction during transverse travel of block 24. Block 24, together with nozzle 20, is caused to reciprocate transversely of the main roll by means of an endless roller chain 31, one of the lengths of which carries a pin 32 which is positioned within a vertical slot 35 in block 24. It will thus be apparent that as the chain, which is suitably supported at each end thereof by sprockets 37, is continuously driven, the supporting block and the nozzle 20 will be moving at a substantially uniform rate transversely of the main roll.

Adjacent the forward edge of the trough 21 are a plurality of feed-in rolls 36, such rolls carrying on their outer surfaces metallic clothing, and the spacing should be such as to cause a slight intermeshing of the clothing. It will be noted that the forward end of nozzle 20 is spaced from feed-in rolls 36, and accordingly there is a reservoir of stock within this area. The stock is thus fed with substantial uniformity to licker-in roll 40 which conveys the stock to main roll 41, the outer surface of which is provided with the usual card clothing 42.

A plurality of units of worker rolls 43 and strip-

per rolls 44 are disposed in spaced relation to the main roll along the lower periphery of the latter. The surface speed of the main roll is, of course, higher than that of the licker-in and of the worker rolls. The surface speed of the stripper 44 is higher than the surface speed of the worker roll 43, thus removing stock from the latter and feeding it back to main roll 41 which has a surface speed greater than stripper 44. The spacing between the outer peripheries of the worker and stripper rolls may be substantially alike, or they may vary, depending upon the particular stock to be carded and other factors. Likewise, the spacing between the pairs of workers and strippers may either be substantially the same or may vary, all as will be appreciated by those skilled in the art.

In the arrangement shown, there are six pairs of workers and strippers in the breaker carding which takes place along the lower periphery of the main roll. This number may also vary, as will be understood. At a point spaced from the last worker roll, fancy roll 45 is journaled, the outer periphery of such roll having the usual fancy clothing. The wires of the fancy are set oppositely from those of the main roll, and surface speed of the fancy may be considerably higher than the surface speed of the main roll. The stock is thus lifted from the wires in a position to be removed from the main roll by means of doffer roll 46, the surface speed of which is relatively slow compared to the surface speed of the main roll. The carded stock is removed from the doffer by means of comb 50 and is disposed in trough 51, a top plan view of which is shown in Fig. 6. The carded stock is delivered as a sliver to throat 52 of trough 51, and thence into tube 53 which is connected with flexible tube 54 having nozzle 55 at its upper end.

40 A blower 56 delivers air up through tube 54, thus causing travel of the sliver through the nozzle and into intermediate trough 60. Nozzle 55 may have a support similar to nozzle 20 shown in Fig. 4, and thus reciprocates transversely of the main roll and builds up a reservoir of the carded stock in the area between the forward edge of nozzle 55 and feed-in rolls 61. This operation causes a lapping back and forth of the sliver, and thus delivers the sliver, the fibres of which have been carded in one direction, namely, parallel with the sides of the sliver, to intermediate licker-in 62, which delivers the stock to main roll 41 wherein the fibres are carded at right angles to the original carding path. A plurality of units of worker and stripper rolls 63 and 64, respectively, are disposed transversely of the main roll above the upper periphery thereof wherein the carding action takes place in substantially the same fashion as it did along the lower periphery thereof.

60 In the preferred arrangement, a larger number of worker and stripper rolls are disposed above the main roll for the finish carding operation, for the reason that there is a different setting of such worker and stripper rolls. In other words, the setting is such as to obtain a finer action. Adjacent the last upper worker roll 63, fancy roll 65 is positioned, and adjacent the fancy the final doffer 66 is disposed. The finished carded web is thus removed from the doffer by comb 67.

65 Referring now to Figs. 1 and 2, it will be noted that the machine includes spaced frame elements 71 which may be secured to the floor by means of floor fittings 72. There is further provided an upper frame structure 73 which is cut away, as

shown at 74. Transverse shaft 75 which supports main roll 41 is journalled in bearing 76 carried by frame element 71. Shaft 75 carries a pulley 77 keyed thereto, such pulley being driven by a belt or other equivalent means 80 which also extends around pulley 81 associated with motor drive 82.

In Fig. 2 there is shown the preferred means for mounting the worker rolls, and a similar arrangement is provided for the stripper rolls. Arms 83 are carried on upper frame member 73 as well as lower frame member 71 in the following manner. Machine bolts 84, which are threaded as shown at 85, pass through openings 86 in arm 83, such openings being of somewhat greater diameter than the diameter of the bolt. These bolts pass into threaded openings 90 in frame 73. Secured to frame 73 is a plate 91 having file teeth or knurls 92, and a similar plate 93 is secured to arm 83. It will be seen from the foregoing that adjustment within reasonable limits of arm 83 radially of shaft 75 may be effected.

Arm 83 at its outer end may have a slot 94 of greater width than the diameter of shaft 95 which carries worker rolls 43 and 63. This slot may extend inwardly from the edge of the arm. A bearing bushing 96 is secured at the outer end of arm 83 by means of bolts 97. These bolts are provided with shoulders 98 and with threaded terminals 99. The shoulder 98 passes through aligned openings 100 in the arm and in the bearing, and the fitting is a precision one so as to effect accurate mounting of the bearing relative to the arm. When it is desired to remove one of the worker rolls, it is only necessary to remove bolts 97 and lift shafts 95 from slots 94. These rolls can thereafter be replaced with the exact setting which they previously occupied.

Shaft 95 may have a hub 103 at its inner end which is force-fitted or otherwise secured in worker roll 43 which is provided with the usual clothing 104 on its outer surface. All the worker rolls are driven by suitable means, such as a belt 105 which engages pulleys 106 and is itself driven by pulley 107 carried on main roll shaft 75. Similar mounting arrangement may be employed for stripper rolls 44 and 64, and these may be driven by a similar drive which is positioned on the side of the machine opposite from that shown in Fig. 1. Doffer rolls 46 and 66 may be driven by belt 110 engaging pulleys 111 with any suitable drive therefor such as a pulley on the main roll.

Feeding means other than that shown may be employed in connection with the main roll, and it will also be appreciated that the novel feed has general utility apart from the present machine.

The arrangement of the clothing on the several rolls is suggestive only and may, of course, be altered to suit varying carding conditions. For instance, the position of the wires on the clothing of the worker rolls may be reversed, and the direction of rotation similarly reversed. This may be done on all or only a part of the worker rolls. Also, the card clothing may be replaced with Garnett clothing, all as will be appreciated by those skilled in the art.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the

invention may be made without departing from the principles thereof.

What I claim is:

1. A carding machine comprising a main roll, a plurality of units of worker and stripper rolls along the lower periphery of the main roll for one carding operation, and a plurality of units of worker and stripper rolls along the upper periphery of the main roll for another carding operation, a first feed, means for removing partially carded stock from the main roll after the first carding operation, an intermediate feed for returning the partially carded stock to the main roll, and means for removing the finished carded material after the final carding operation.
2. A carding machine comprising a main roll, a plurality of carding sections which extend around substantially the entire periphery of the main roll, each carding section being arranged for a separate carding operation, each carding section including a plurality of units of worker and stripper rolls disposed in spaced relation to the main roll, a first feed adjacent the beginning of the first carding section for delivering the stock to the main roll for carding the fibres in a direction generally perpendicular to the axis of the main roll, means for removing partially carded stock from the main roll adjacent the end of the first carding section, an intermediate feed for returning the partially carded stock to the main roll adjacent the beginning of a succeeding carding section with the fibres of the stock disposed generally parallel with such axis, and means for removing the stock after the second carding operation.
3. A carding machine comprising a main roll, a plurality of units of worker and stripper rolls disposed in spaced relation along the lower periphery of the main roll for one carding operation, and a plurality of units of worker and stripper rolls in spaced relation along the upper periphery of the main roll for another carding operation, a first feed, means comprising fancy and doffer rolls for removing partially carded stock from the main roll after the first carding operation, an intermediate feed for returning the partially carded stock to the main roll, and means for removing the finished carded material after the final carding operation.
4. A carding machine comprising a main roll, a plurality of carding sections which extend around substantially the entire outer periphery of the main roll, each carding section including a plurality of units of worker and stripper rolls disposed in spaced relation to the main roll, a first feed for delivering the uncarded stock to the main roll in the first carding section, means comprising fancy and doffer rolls for removing the partially carded stock at the end of the first section, an intermediate feed for delivering the partially carded stock for carding in the second carding section in a second direction from the first carding operation, and fancy and doffer rolls for removing the finished carded material after the second carding operation.
5. In the art of carding on a carding machine provided with a main roll and a plurality of units of worker and stripper rolls disposed around substantially the entire outer periphery of the main roll, the method which consists in feeding the uncarded stock to the main roll and carding to fibres in one direction which is generally perpendicular to the axis of the main roll, removing the partially carded stock from the main roll at a point substantially 180° from the point of initial

feed, then re-feeding the partially carded stock to the main roll at a point adjacent to but spaced from the point of such removal with the fibres thereof being disposed generally parallel with such axis for a second carding operation, and then removing the carded material from the main roll at a point adjacent the first feed.
